UNITED STATES PATENT OFFICE.

WILLIAM CURLETT, OF SAN FRANCISCO, CALIFORNIA.

REINFORCED CONCRETE CONSTRUCTION.

No. 845,763.

Specification of Letters Patent.

Patented March 5, 1907.

Application filed October 29, 1906. Serial No. 341,087.

To all whom it may concern:

Be it known that I, WILLIAM CURLETT, a citizen of the United States, residing at San Francisco, in the county of San Francisco and State of California, have invented new and useful Improvements in Reinforced Concrete Construction, of which the following is a specification.

My invention pertains to reinforced concrete constructions; and it contemplates the provision for use in such a construction of a reinforcing-bar of metal or other material compatible with its function, constructed with a view of forming a bond between bar and concrete and of holding itself against endwise movement in either direction in the concrete, while at the same time tending to prevent disintegration of the concrete and in that way lending strength and durability to the same.

Other objects and advantages of the invention will be fully understood from the following description and claim when the same are read in connection with the accompanying drawings, forming part of this specification, in which—

Figure 1 is a view of a reinforced concrete construction in which the bar constituting the present and preferred embodiment of my invention is employed. Figs. 2 and 3 are projected views of adjacent surfaces of the bar. Fig. 4 is a transverse section of the bar, taken in the plane indicated by the line 4-4, extending through Figs. 2 and 3. Fig. 5 is a perspective view of the reinforcing-bar.

Similar letters designate corresponding parts in all of the views of the drawings, referring to which—

A is a body of concrete or analogous material, and B is my novel reinforcing-bar, which may be arranged horizontally, vertically, or otherwise in the concrete, as occasion demands. The said bar B is preferably, though not necessarily, made of steel or of metal capable of withstanding considerable weight and strain, and it is peculiar in that it is of double or compound dovetail formation—that is to say, it is provided at opposite sides with walls C, which converge in one direction to abrupt shoulders D, while on its other sides, adjacent to those first mentioned, it has walls E, which are converged in the opposite direction to abrupt shoulders F. This arrangement of the double dovetails of the bar in reverse order will be better appreciated

when Figs. 2 and 3 of the drawings are compared, and by reference to the said figures it will be apparent that the shoulders F complementary to the dovetails E are arranged in different transverse planes from the shoulders D complementary to the opposite dovetails C. From this it follows that the provision of the shoulders F and D at frequent intervals in the length of the bar does not seriously weaken the same, and it also follows that the bar is provided back of the shoulders D with comparatively thick portions G for resisting pressure in one direction and is provided back of the shoulders F with comparatively thick portions H, calculated to resist pressure in the opposite direction. It will also be apparent from the foregoing that the dovetails and the abrupt shoulders at the several sides of the bar form interstices or recesses in which the concrete may rest after the manner shown in Fig. 1, with the result that a strong bond is formed between bar and concrete, and casual endwise movement of the bar in either direction in the concrete is precluded and at the same time the bar is enabled to lessen the liability of the concrete becoming disintegrated, and hence the strength and durability of the body of concrete are materially enhanced.

While my novel bar is possessed of the advantageous double-dovetail formation described and has the dovetails at adjacent sides arranged in reversed order, it will be appreciated that the said bar is susceptible of being produced almost, if not quite, as easily and cheaply as the reinforcing-bars at present in use.

The construction of bar herein shown and described constitutes the best embodiment of my invention at present known to me; but I desire it understood that in practice such changes in the form, construction, and relative arrangement of the bar may be made as fairly fall within the scope of my invention as claimed.

Having described my invention, what I claim, and desire to secure by Letters Patent, is—

A reinforcing-bar for use in concrete and analogous constructions, having at opposite sides shoulders D disposed at right angles to its length and walls C which extend between the shoulders D and each converge in one direction from one shoulder D to the next adjoining shoulder D, and also having at its

other sides adjacent to those first-mentioned, shoulders F disposed at right angles to its length and walls E which extend between the shoulders F and each converge in 5 the opposite direction, with reference to the walls C, from one shoulder F to the next adjoining shoulder F.

In testimony whereof I have hereunto set my hand in presence of two subscribing witnesses.

WILLIAM CURLETT.
